UNITED STATES PATENT OFFICE

2,521,040

CONDENSER FOR REFRIGERATORS

Lee W. Casetta, Fond du Lac, Wis.

Application June 11, 1945, Serial No. 598,720

7 Claims. (Cl. 62—115)

1

My invention relates to an improvement in condensers for refrigerators and the like. It has for one object to provide an improved condenser for use in a refrigerating cycle.

Another purpose is to provide an improved condenser structure for refrigerators, in which the high pressure pipe from the compressor is associated with the returning suction line in a finned condenser structure.

Another purpose is to provide a system for effecting cooling of the condenser in relation to the surrounding air temperature and for thus reducing high head pressure on the compressor.

Other purposes will appear from time to time throughout the specification and claims.

I illustrate my invention more or less diagrammatically in the accompanying drawings, wherein—

Figure 1 is a diagrammatic illustration of a refrigerating system in which my invention is employed;

Figure 2 is a section on an enlarged scale on the line 2—2 of Figure 1;

Figure 3 is a section on an enlarged scale on the line 3—3 of Figure 1;

Figure 4 is a similar section through a variant form;

Figure 5 is a side elevation of a variant form of condenser with parts in section;

Figure 6 is a section on an enlarged scale along the line 6—6 of Figure 5;

Figure 7 illustrates my invention applied to a hermetic compressor in connection with a condenser which may be cooled by natural draft;

Figure 8 is a side elevation of the structure shown in Figure 7; and

Figure 9 is an end elevation of the structure shown in Figures 7 and 8.

Like parts are indicated by like characters throughout the specification and drawings.

Referring to the drawings, I generally indicate any suitable compressor, the details of which do not form part of the present invention. 2 is any suitable motor through which the compressor may be driven by the belt 3 and the driven pulley 4. 5 indicates diagrammatically any suitable evaporator. 6 generally indicates the condenser; 7 generally indicates the receiver and 8 any suitable expansion valve. The high pressure vapor line 10 extends from the compressor to the condenser 6. 11 is any suitable suction or return line for returning vaporized refrigerant from the evaporator to the compressor. 12 are any suitable fins for the evaporator. As will be clear from Figure 1, the high pressure

2

vapor line, as it enters communication with the fins 12, or before, is associated with the suction return line 11, the two being secured together in any suitable manner by welding, brazing or the like, or with a press fit.

Whereas I have described and shown a conventional belt driven reciprocating piston condenser, it will be understood that my invention is equally effective if used with a hermetic or sealed condensing unit. It will also be understood that my invention is equally applicable whether a static condenser or a forced draft condenser is employed.

In Figure 3 I illustrate the pipes 10 and 11 as welded together. I may, however, employ a double pipe structure as at 10a, 11a in Figure 4, which constitutes in effect a single pipe defining two ducts. At or near the point at which the pipes leave the finned structure, they diverge as at B, the suction pipe 11 returning to the intake of the compressor 1 and the high pressure line 10, delivering liquefied refrigerant to the receiver 7. The high pressure liquid refrigerant flows from the receiver 7 along the pipe 13 to any suitable expansion valve 8, whence it reaches the evaporator 5 at reduced pressure and is evaporated therein.

In the form of Figures 5 and 6, the structure is varied by carrying the high pressure pipe 10b inside of the suction pipe 11b as the two pipes pass through the fin structure 12a. Otherwise the arrangement is shown in Figure 1.

Referring to Figures 7, 8 and 9, 20 generally indicates any suitable hermetically sealed compressor the details of which do not form part of the present invention. It will be understood, however, that the motor component and a compressor component are housed within an outer casing. The casing is mounted for example by supports 21 upon a finned condenser structure generally indicated as 22 which includes a plurality of individual fins 23. 24 illustrates the suction or return duct from the evaporator not herein shown, to the compressor unit 20. 25 illustrates the high pressure duct extending from the compressor through which the refrigerant is delivered under pressure for passage through the condenser. It will be observed that, at a short distance from the compressor unit, the high pressure delivery duct 25 extends into and is enclosed by the suction or return duct 24. Thus the duct 24, as it extends through and in contact with the fins 23, encloses the high pressure delivery duct 25. The end of the high pressure duct 25a extends from any suitable

block or fitting 30, mounted as upon a support 31, upon the condenser assembly 22. Extending therefrom is any suitable continuing duct not herein shown which may extend to a receiver or directly to an evaporator not herein shown. The general circuit may be as shown diagrammatically in Figure 1. 32 generally indicates any suitable fitting or connection to which the part of the suction or return duct which extends from the evaporator may be connected.

It will be understood that whereas in Figures 7, 8 and 9, I have illustrated the high pressure supply duct as enclosed within the return duct or suction duct 24, the two ducts may be related as shown in Figures 3 and 4.

It will be realized that whereas I have shown and described an operative structure, still many changes might be made in the size, shape, arrangement and number of parts without departing materially from the spirit of my invention. I wish, therefore, that my showing be taken as in a broad sense diagrammatic and illustrative, rather than limiting me to my precise showing.

The use and operation are as follows:

I provide a system for effective cooling of the condenser in relation to the surrounding air temperature. My structure reduces high head pressure on the compressor in the condenser and in the liquid receiver. As cold gas or evaporated refrigerant returns from the evaporator 5 through the suction pipe 11 to the compressor, it joins the high pressure pipe 10 along which the refrigerant is delivered at high pressure from the compressor to the condenser. The cold gas or vapor in the suction pipe 11 transmits its cooling effect to the contents of the high pressure pipe 10. As the pipes pass together through the finned structure of the condenser, heat from the hot discharge or high pressure pipe 10 is transmitted to the contents of the cold low pressure or suction pipe 11. The result is a substantial improvement in the efficiency of the unit. It tends to reduce the high pressure of hot compressed refrigerant as it leaves the compressor. It also helps to cause the evaporation of such liquid refrigerant as may be flowing toward the compressor through the suction or return pipe 11. This reduces the work of the compressor and tends to reduce the slugging of oil through the compressor valves, which slugging may at times produce objectionable loud knocking noises.

It will be understood that the hot high pressure pipe and the cold suction or return pipe may be associated with each other in a variety of ways. The two pipes may be welded, soldered or tinned to each other as shown in Figure 3, or they may be molded together or unitarily formed as shown in Figure 4. The high pressure pipe 10b may also conveniently be inserted in and carried through the low pressure or suction pipe 11b as shown in Figures 5 and 6. Thus the high pressure pipe 10 is subjected not only to the cooling effect of the condenser fins 12 but also to the cooling effect of the cold return pipe 11. Where the form of Figures 5 and 6 are employed, the high pressure, high temperature pipe 10b is surrounded by the cold contents of the low pressure return pipe 11b, the hot refrigerant and the cold refrigerant being separated only by the heat-conductive wall of the pipe 10b.

I find it advantageous as shown in Figures 7, 8 and 9 to put the refrigerant returning through the return duct 24 in thermal contact with that

part of the high pressure refrigerant duct 25 which extends from the compressor assembly 20 to the finned condenser. The thermal contact between the returning refrigerant and the refrigerant delivered under compression may be quite effective even without contact in the condenser itself, because the hottest discharge gas leaving the compressor is the high pressure refrigerant vapor in that part of the high pressure duct 25 which extends directly from the compressor unit to the finned condenser itself. However, it is advantageous, as shown in Figures 7, 8 and 9 to maintain the thermal connection throughout the entire length of passage of the high pressure duct 25 through the condenser.

I claim:

1. In a refrigerating apparatus, a compressor and means for actuating it, an evaporator, a suction return pipe extending from said evaporator to said compressor, a condenser, said suction return pipe extending through said condenser, a high pressure delivery pipe extending from said compressor to said evaporator and forming part of the condenser, said suction return pipe and high pressure delivery pipe being in heat exchange relationship as they pass through said condenser.

2. In a refrigerating apparatus, a compressor and means for actuating it, an evaporator, a suction return pipe extending from said evaporator to said compressor, a high pressure delivery pipe extending from said compressor to said evaporator, pressure reduction means, in the line of delivery of said high pressure pipe to the evaporator, and a condenser structure including a part of the high pressure pipe, and a part of the suction return pipe, in direct heat transfer relationship with each other, and a plurality of fins in heat transfer relationship with both pipes where they are in such relationship with each other.

3. In a refrigerator system including a compressor and means for actuating it, an evaporator, a high pressure duct extending from said compressor to said evaporator, pressure reduction means, in said duct, between the compressor and the evaporator and a suction return pipe from said evaporator to said compressor, said suction return pipe being in heat exchange relationship with said high pressure pipe adjacent the point at which said high pressure pipe leaves the compressor.

4. In a refrigerator system including a compressor and means for actuating it, an evaporator, a high pressure duct extending from said compressor to said evaporator, pressure reduction means, in said duct, between the compressor and the evaporator and a suction return pipe from said evaporator to said compressor, said suction return pipe being in heat exchange relationship with said high pressure pipe adjacent the point at which said high pressure pipe leaves the compressor, said high pressure pipe extending into and being surrounded by said suction return pipe.

5. In a refrigerator system including a compressor and means for actuating it, an evaporator, a high pressure duct extending from said compressor to said evaporator, pressure reduction means, in said duct, between the compressor and the evaporator and a suction return pipe from said evaporator to said compressor, said suction return pipe being in heat exchange relationship with said high pressure pipe from adjacent the point at which said high pressure

pipe leaves the compressor and for a substantial distance therealong.

6. In a high side unit for a refrigerating system, a hermetic compressor-motor assembly, a condenser including a plurality of fins, a suction return line in heat exchange relationship with said fins, extending to the compressor component of said assembly, and a high pressure pipe extending from the compressor component and in heat exchange relationship with said fins and with said low pressure return pipe.

7. In a refrigerating apparatus, a compressor, and means for actuating it, an evaporator, a high pressure delivery pipe extending from the compressor to the evaporator, and a suction return pipe extending from the evaporator to the compressor, the two pipes being, for a portion of their length, in heat exchange relationship, a plurality of fins in heat exchange

relationship with those portions of the pipes which are in heat exchange relationship with one another.
